[57] CLAIM

The ornamental design for a hand held roller massager, as shown and described.

DESCRIPTION

FIG. 1 is a left side elevational view of a hand held roller massager showing our new design, the opposite side being a mirror image thereof;

FIG. 2 is a top plan view thereof, the bottom view being a mirror image thereof;

FIG. 3 is a front elevational view thereof; and

FIG. 4 is a rear elevational view thereof.

FIG. 1

FIG. 2

FIG. 3

FIG. 4
